LASTING MACHINE

Theodore P. Courchene, Beverly, Mass., assignor
to United Shoe Machinery Corporation, Flem-
ington, N. J., a corporation of New Jersey

Application June 6, 1950, Serial No. 166,389

17 Claims. (Cl. 12—8.1)

1

This invention relates to lasting machines, and is herein shown as applied to a machine organization of the same general character as disclosed in United States Letters Patent No. 1,843,232, granted on February 2, 1932, on an application of B. Jorgensen. While it is an object of the invention, in one aspect, to improve an organization of that character, it is to be understood that the invention is not thus limited in its applicability.

Machines such as shown in the above-mentioned Letters Patent are frequently used for lasting tennis shoes or the like which are commonly made on metal lasts and in the lasting of which the uppers are secured to insoles by adhesion. In such a machine the shoe is positioned bottom upward and is operated upon by opposite side-lasting mechanisms which wipe the upper lengthwise of the last in response to downward movement of the last, these mechanisms including flexible straps which engage the upper frictionally. Associated with the flexible straps are lasting fingers which act thereafter through the straps to lay the marginal portion of the upper inwardly over the insole and to press it down into position to adhere to the insole. As described in the above-mentioned Letters Patent, the side-lasting mechanisms are thus operated first to last the shank portion of the shoe adjacent to its heel end and thereafter are moved a short distance lengthwise of the shoe toward its toe end and repeat their operations on the shoe.

The present invention, as applied to an organization of the character above outlined, provides the opposite side-lasting mechanisms with novel means arranged to cooperate with the flexible lasting straps in controlling the upper. The construction shown comprises members arranged to clamp the marginal portion of the upper against some of the straps, together with means by the action of which these members are caused to assume the required clamping positions without any attention on the operator's part. More particularly, in order not to interfere with the presentation of the work to the machine, the clamp members are held initially by a latch in outwardly retracted positions against the lasting straps, and in response to the movement of an arm whereby the operator starts the power operation of the machine the members are released by the latch. Upon such release they are moved inwardly and upwardly by springs to positions over the shoe bottom beyond the upstanding marginal portion of the upper, and immediately thereafter a cam with which the machine is provided moves them reversely downward and out-

2

ward to positions in which they clamp the upper against the straps. It will be understood that the clamp members, in cooperation with the straps, afford better insurance that the upper will be conformed tightly and smoothly to the contour of the last and will be laid inwardly over the insole in the proper manner without the presence of any objectionable wrinkles. Prior to the completion of the laying of the upper inwardly over the insole its marginal portion slips out from between the clamp members and the straps, means being provided for moving the clamp members a short distance upwardly to insure their release of the upper. Since the use of the clamp members is not required when the side-lasting mechanisms operate the second time on the shoe, they are released by the above-mentioned cam and are again moved inwardly and upwardly to positions over the shoe bottom by the springs after the first operations of the mechanisms, remaining in such idle positions during the second operations of the mechanisms. Near the end of the cycle a rise on the cam returns the clamp members to their initial positions against the lasting straps, after which the latch, released by return movement of the starting arm, retains them in those positions.

The novel features of the invention will now be more particularly described with reference to the accompanying drawings and thereafter pointed out in the claims.

In the drawings,

Fig. 1 is a view in front elevation of portions of the machine to which the invention is herein shown as applied, the parts being shown as they appear shortly after the starting of the cycle of operations;

Fig. 2 is a detail view mainly in left-hand side elevation of a portion of the structure shown in Fig. 1;

Fig. 3 is a view mainly in right-hand side elevation, with parts broken away, showing the opposite side-lasting mechanisms in their initial positions;

Figs. 4, 5, and 6 are views similar to Fig. 3 of portions of the structure, but showing the parts in positions assumed at different times in the operation of the machine;

Fig. 7 is a section on the line VII—VII of Fig. 6; and

Fig. 8 is a view partly in left-hand side elevation and partly in section, showing a portion of the means for controlling the side-lasting mechanisms with the parts as they appear at the time in the cycle represented by Fig. 1.

In view of the disclosure in the above-men-

tioned Letters Patent, the drawings show only portions of the complete machine and the description will be confined to such parts as it is necessary to refer to for an understanding of the invention. The machine includes a heel-end support 2 (Fig. 1) mounted to slide downwardly in guideways in the frame against the resistance of a spring 4 and carrying a last pin 6 herein shown as extending upwardly into a spindle hole formed in the heel end of a metal last of the kind on which it is customary to make tennis shoes and the like. The last with the upper loosely mounted thereon is positioned by the operator on the last pin 6 in presenting it to the machine, and after opposite side-lasting mechanisms, hereinafter described, have been moved inwardly against the upper on the sides of the last the operator places an insole on the bottom of the last. The toe end of the last and shoe thus positioned is supported on a toe rest 8 which is movable downwardly against the resistance of a spring 10. The machine includes mechanisms which need not be described for lasting the toe and heel ends of the shoe. Near the beginning of the cycle of operations the shoe is moved downwardly relatively to the side-lasting mechanisms with the heel-end support 2 and the toe rest 8 by a heel presser foot 12 engaging the heel end of the insole and a toe presser foot 14 engaging the toe end of the insole, thus causing the side-lasting mechanisms to wipe the upper heightwise of the last between the heel-end portion and the ball portion of the shoe. These mechanisms are then operated to lay the margin of the upper inwardly over the shank portion of the insole and to press it down into position to adhere to the insole. Thereafter the side-lasting mechanisms are retracted from the shoe, are moved a short distance lengthwise of the shoe toward its toe end and are again operated to complete the lasting of the sides of the shoe between the portion first operated upon thereby and the portion operated upon by the toe-lasting mechanism. The operations thus briefly outlined are more fully described in the above-mentioned Letters Patent.

As further disclosed in said Letters Patent, the toe presser foot 14 is carried by an arm 16 which the operator swings forwardly about a vertical axis by means of a handle 18 thereon to position the presser foot over the shoe prior to its downward movement, and this swinging movement of the arm serves to start the cycle of operations of the machine. For this purpose a vertical rod or post 20 to which the arm 16 is secured and which is turned by the swinging of the arm imparts similar turning movement to a collar 22 extending around it, this collar corresponding to the collar 400 shown in said Letters Patent. By its turning movement this collar imparts lengthwise rearward movement to a rod 24 (Fig. 2) the rear end of which engages a screw 26 mounted in one arm of a bell-crank lever 28 pivotally mounted on a bracket on the frame. The other arm of the bell-crank lever is connected by a downwardly extending link 30 to an arm 32 by upward swinging movement of which a clutch 34 is tripped to start the cycle of operations. Through the connections described the arm 32 is thus swung upwardly by the forward swinging movement of the arm 16. The clutch 34 is mounted on a cam shaft 36 by the turning of which operative movements are imparted to the various operating mechanisms.

In general accordance also with the disclosure of the above-mentioned Letters Patent, each of

the opposite side-lasting mechanisms, identified generally by the reference character 38, includes a casing 40 mounted to swing toward and from the shoe on a rod 42 which is moved lengthwise to carry the mechanism a short distance toward the toe end of the shoe after its first operation on the shank portion of the shoe adjacent to its heel end. Mounted to swing about each rod 42 within the casing 40 is an arm 44 (Fig. 3) arranged to control a plurality of lasting fingers 46 extending generally widthwise of the shoe and preferably four in number. Associated with these fingers are flexible lasting straps 48, preferably made of leather, through which the fingers act on the upper, the straps extending heightwise of the shoe and outwardly over the fingers. In the construction herein shown there is one strap common to the two fingers which are nearest to the heel end of the shoe and another strap common to the two fingers which are nearest to the forepart of the shoe. Associated with each strap are two side pressers each comprising an arm 50 pivotally mounted on a rod 52 on the casing 40 to swing widthwise of the shoe and having pivotally mounted on a pin 54 on its upper end a block 56 arranged to press the strap against the side of the shoe, the lower end of the strap being secured to the block. One of the two arms 50 associated with each strap is engaged by a pin 58 slidably mounted in the casing 40 and controlled by a spring 60 which tends to swing the arm inwardly toward the shoe, such swinging movement of the arm being limited by engagement of a lug 62 on the lower end of the arm with a plate 64 on the casing 40. The other of the two arms 50 is similarly controlled by a spring 66 connected to a finger 68 on the lower end of the arm and to a pin on the casing 40, the finger 68 engaging the plate 64 to limit the swinging of the arm by the spring. It will thus be seen that when the side-lasting mechanisms 38 are swung inwardly toward the shoe the blocks 56 adjust themselves to the shoe and press the straps 48 yieldingly against the sides of the shoe under the influence of the springs 60 and 66.

Each of the four lasting fingers 46 of each side-lasting mechanism has therein a slot 70 (Fig. 3) and through the slots in the several fingers extends a rod 72 which, in the construction herein shown, is carried by a yoke 74 (Fig. 7) secured on the upper end of the arm 44. Slidably mounted in each finger and engaging the rod 72 is a pin 76 pressed outwardly against the rod by a spring 78. Accordingly, at the appropriate time in the operation of the machine, the rod 72 acts through the pins 76 and the springs 78 to force the fingers 46 yieldingly inward over the bottom of the shoe to lay the margin of the upper over the insole in response to inward swinging movement of the arm 44 while the casing 40 is substantially stationary. The straps 48 are connected at their outer ends to blocks 80 slidably movable in inward directions in the fingers 46 against the resistance of springs 82. The fingers, therefore, may slide along the straps as they are moved inwardly over the bottom of the shoe. Under each finger is a plunger 84 pressed upwardly by a spring 86 in the yoke 74, the several springs thus tending to swing the fingers upwardly and thereby maintaining the straps in a taut condition.

Connected to the two casings 40 and tending to swing them inwardly toward the shoe is a spring 88 against the resistance of which they are swung to their outermost positions by the

arms 44. For this purpose, in the construction herein shown, each arm carries a stud 90 arranged to engage the casing 40 at the outer end of a slot 92 in the casing. For controlling and operating the arms 44 there are provided two toggle links 94 pivotally connected near their outer ends to the arms by means of pins 95 and pivotally mounted at their inner ends on a rod 96, the two toggle links being also mounted to slide lengthwise of the rod 96 to permit them to be moved lengthwise of the shoe with the side-lasting mechanisms. The rod 96 is supported in the upper end of a downwardly extending link 98 which corresponds to the link 646 shown in the previously mentioned Letters Patent. As shown in Fig. 8, the link 98 is pivotally connected at its lower end to a lever 100 pivotally mounted on a rod 102 on the frame, and this lever is connected by a two-part link 104 to a lever 106 pivotally mounted on a shaft 108. One part 110 of the link 104 is connected to the lever 100 and is hollow to provide a housing for a plunger 112 on the upper end of a rod 114 which serves as the other part of the link and which is connected to the lever 106. A spring 116 engaged by the plunger 112 is arranged to be compressed by downward movement of the rod 114 relatively to the part 110 of the link to provide a yielding operating connection between the lever 106 and the lever 100. The lever 106 carries a roll 118 arranged to be engaged by a path cam 120 formed in one side of a cam wheel 122 on the cam shaft 36. Initially the arms 44 and the casings 40 of the side-lasting mechanisms are held in their outermost positions, in which they are shown in Fig. 3, by a pivotally mounted latch lever 124 which holds the lever 100 upraised. Prior to the starting of the machine this latch lever is operated to release the lever 100 by movement of a plunger 126 which the operator pushes rearwardly with his knee, the means for operating the latch lever by the movement of the plunger being more fully described in the previously mentioned Letters Patent. The release of the lever 100 renders the spring 88 effective to swing the side-lasting mechanisms inwardly toward the shoe and thus to cause the straps 48 to be pressed yieldingly against the upper by the arms 50 and the blocks 56, as hereinbefore described and as shown in Fig. 4, ready to wipe the upper heightwise of the last in response to downward movement of the shoe after the starting of the machine. Such inward movements of the side-lasting mechanisms are permitted by the fact that initially the roll 118 lies in a widened portion 128 of the path cam 120. This cam is so formed that after the downward movement of the shoe the arms 44 are swung farther inwardly to cause the fingers 46, acting through the straps 48, to lay the marginal portion of the upper over the insole in the manner hereinbefore described. As the fingers are thus moved inwardly their inner ends are forced downwardly toward the bottom of the shoe against the resistance of the spring-controlled plungers 84 by the pull of the straps thereon. Further to increase the downward pressure on the upper over the insole, an extension 130 of each of the toggle links 94 is arranged to act through a sleeve 132 and a spring 134 to move a device 136 upwardly into position to swing the fingers 46 about the rod 12 in the direction to depress their inner ends. The cam 120 is further so formed as to withdraw the side-lasting mechanisms from the shoe preparatory to the movement thereof toward the toe end of the shoe 75

and thereafter to cause them to operate on the shoe the second time, means being provided for preventing them from being caught and held by the latch lever 124 when they are thus withdrawn, as disclosed in detail in the above-mentioned Letters Patent.

For purposes of this invention the yokes 74, secured as hereinbefore described to the upper ends of the arms 44, are each provided with upwardly extending side portions which are spaced apart and in the upper ends of which is mounted a shaft 138 (Figs. 3 and 7). Between the upwardly extending side portions of each yoke is a holder 140 which, by means of members 141 thereon, is hung on the shaft 138 and provides a guideway for a rack bar 142 extending widthwise of the shoe, the teeth on the rack bar being engaged by a pinion 144 fast on the shaft 138 between the members 141. Pivotally mounted on a pin 146 on the inner end of the rack bar 142 is a downwardly extending finger 148 which serves as a clamp member for clamping the marginal portion of the upper against one of the lasting straps 48. A spring 150 connected to the finger and to a lug 152 on the rack bar 142 tends to swing the finger in an outward direction, its swinging movement in this direction, when it is not in engagement with the upper or with the lasting strap, being limited by its engagement with the end of the rack bar. By swinging movements of the holder 140 about the shaft 138 the finger 148 may be moved upwardly and downwardly, its downward movement being limited by engagement of the head of a screw 154 on the rack bar 142 with one of the lasting straps 48 and its upward movement being limited by engagement of the holder 140 with a crosspiece 156 carried by the yoke 74. Secured to one side portion of the yoke 74 are plates 158 and 160 which cooperate with that portion of the yoke to provide a guideway for another rack bar 162 extending upwardly and downwardly, the teeth of this rack bar engaging a pinion 164 fast on the shaft 138. Pivotally connected to the lower end of the rack bar 162 is a link 166 the lower end of which is pivotally connected to one end of a lever 168 pivotally mounted between its opposite ends on the previously mentioned stud 90 carried by the arm 44. Connected at one end to a lug 170 on the link 166 and at its other end to a pin 172 on the casing 40 is a spring 174 which tends to move the rack bar 162 in a downward direction and thereby to move the rack bar 142 in an inward direction, such inward movement of the rack bar 142 being limited by engagement of a pin 176 on its outer end with the holder 140. It will be evident that after the pin has engaged the holder the spring 174 further tends to swing the holder about the axis of the shaft 138 in the direction to raise the finger 148; this movement being limited by engagement of the holder with the crosspiece 156. Accordingly, the springs 174 associated with the opposite side-lasting mechanisms, when permitted by means hereinafter described for controlling the levers 168, move the rack bars 142 inwardly and swing them upwardly to carry the fingers 148 from initial positions in which they are shown in Fig. 3, where they are held by the springs 150 yieldingly in engagement with the straps 48, to the positions over the shoe bottom in which they are shown in Fig. 4.

For controlling the levers 168 there is mounted for turning movement in brackets 178 secured on the vertically movable heel-end support 2 a shaft 180 having fast thereon a pair of arms 182 pro-

vided with laterally extending lugs 184 arranged to overlie and engage rolls 186 on the levers 168. It will be understood that the lugs 184 extend far enough to insure cooperative relation between them and the rolls 186 notwithstanding such bodily movements as are imparted to the levers 168 by the swinging of the arms 44. Extending from one of the arms 182 is an arm 188 (Figs. 1 and 3) connected by a link 190 to one end of a lever 192 pivotally mounted between its opposite ends on a member 194 fast on the vertically movable heel-end support 2. The other end of the lever 192 is connected by a downwardly extending link 196 to a lever 198 mounted to swing about a shaft 200. Connected to the lever 198 is a spring 202 which tends to swing it upwardly. It will thus be seen that when the lever 198 is swung in a downward direction it swings the lever 192 in a clockwise direction with reference to Fig. 1 and, through the link 190, swings the arms 182 in a downward direction. By the engagement of the lugs 184 of these arms with the rolls 186 on the levers 168 these levers are swung in directions to impart upward movements to the rack bars 162 against the resistance of the springs 174 and thereby to move the rack bars 142 in outward directions. By reason of friction and gravity the first result of such upward movements of the rack bars 162 is to swing the holders 140 and the rack bars 142 in the directions to carry the clamp fingers 148 downwardly, these movements being limited by engagement of the screws 154 with the straps 48. In this manner the clamp fingers 148 are carried downwardly and outwardly into positions to engage the straps 48 or, at the appropriate time, to clamp the marginal portion of the upper against the straps. Initially, as already suggested, the clamp fingers 148 are held in retracted positions against the straps 48 as shown in Fig. 3, thus providing room for the mounting of the last, with the upper thereon, on the last pin 6 and the placing of the insole on the bottom of the last. For holding the clamp fingers in these positions there is further provided a latch 204 (Figs. 1 and 3) pivotally mounted on a member 206 on the base of the machine and arranged to engage the head of a stud 208 whereby the link 196 is pivotally connected to the lever 198. A spring 210 connected to the latch tends to swing it into position thus to hold the fingers 148, in which position it is shown in Fig. 3.

For causing the clamp fingers 148 to be moved by the springs 174 from the positions in which they are shown in Fig. 3 to the positions in which they are shown in Fig. 4, mechanism is provided for swinging the latch 204 to release the lever 198 by the forward swinging movement of the arm 16 whereby, as hereinbefore described, the operator starts the cycle of operations of the machine by tripping the clutch 34. This mechanism includes a bar 212 secured to the link 38 which is moved upwardly by the forward movement of the arm 16, the bar 212 being connected by a link 214 to a bell-crank lever 216 pivotally mounted on a member 218 on the base of the machine and this bell-crank lever being connected by a long link 220 to the latch 204. As the parts are shown in Fig. 1, the latch has been swung into position to release the lever 198 by the forward swinging movement of the arm 16.

When the lever 198 is released by the latch 204 as above described, it is swung upwardly by the spring 202 to carry a roll 222 thereon into engagement with a cam 224 on the cam shaft 36. In

response to this upward movement of the lever 198 the arms 182 are swung upwardly, thus causing the springs 174 to move the clamp fingers 148 to the positions shown in Fig. 4. Immediately after the starting of the cycle of operations a rise 226 on the cam 224 swings the lever 198 downwardly to cause the arms 182 to swing the levers 168 in the directions to move the clamp fingers 148 downwardly and outwardly in the manner hereinbefore described to clamp the marginal portion of the upper against the straps 48 as illustrated in Fig. 5. Substantially at the same time the shoe is moved downward a short distance by the heel-presser-foot 12 and the toe-presser-foot 14 to cause the straps 48 to wipe the upper heightwise of the last, Fig. 5 showing the parts as they appear after such downward movement of the shoe. It will be evident that since the arms 182 and the lever 192 are carried by the downwardly movable heel-end support 2, the tendency of such movement of the support is to cause the arms 182 to swing in upward directions, but this is substantially compensated for by the fact that the arms are carried bodily downward by the support. The rise 226 on the cam holds the lever 198 depressed until the lasting fingers 46 have been moved inwardly to lay the marginal portion of the upper over the insole as illustrated in Fig. 6. Before the fingers 46 have completed their inward movements the margin of the upper slips out from between the clamp fingers 148 and the straps 48. To afford better insurance that regardless of the width of the marginal portion of the upper extending inwardly over the insole it will always be released by the clamp fingers by the time the lasting fingers 46 have completed their inward movements, there is pivotally mounted on a stud 228 (Figs. 4 and 7) on one side of each of the yokes 74 a lever 230 having an inwardly extending arm 232 provided with a pin 234 arranged to underlie the holder 140 in which the rack bar 142 is mounted. Adjustably secured to the casing 40 by two screws 236 (Fig. 7) is a bar 238 in the upper end of which is mounted a pin 240 arranged to engage the upper face of an outwardly extending arm 242 of the lever 230 in response to the inward swinging movement of the arm 44 relatively to the casing 40 and thereby to swing the lever 230 in the direction to raise the clamp finger 143 (see Fig. 6). The screws 236 extend through a slot 244 in the bar 238 to permit such adjustment of the bar as to vary the amount of upward movement thus imparted to the clamp finger.

When the side-lasting mechanisms operate the second time on the shoe as hereinbefore described, after they have been moved a short distance lengthwise of the shoe toward its toe end, conditions are such that the use of the clamp fingers 148 is unnecessary and even undesirable. Prior to the second operations of the mechanisms, therefore, the rise 226 on the cam 224 releases the lever 198, whereupon the springs 174 move the clamp fingers again inwardly and upwardly to idle positions such as illustrated in Fig. 4. Machines such as shown in the previously mentioned Letters Patent are provided with shoe-removing mechanism which is swung downwardly over the shoe into position to grip the shoe and thereafter removes the shoe from the shoe-supporting means. In order to prevent interference between the shoe-removing mechanism and the clamp fingers 148 and their supports, the cam 224 has thereon a second rise 246 which engages the roll 75 222 and swings the lever 198 downwardly toward

the end of the cycle of operations. By this downward swinging movement of the lever the clamp fingers 148 are returned to positions in engagement with the lasting straps 48. Before the rise 246 on the cam releases the lever 198, the arm 16, after moving upwardly away from the shoe, is swung rearwardly and thereby causes the latch 204 to be swung by its spring 210 into position again to hold the lever 198 against upward movement.

The manner of operation of the machine, in so far as it is of interest with reference to the present invention, will now be briefly summarized, the operations of the toe and heel lasting mechanisms being disregarded. The operator mounts a last with an upper loosely assembled thereon on the last pin 6, the opposite side-lasting mechanisms 38 occupying at this time their initial outwardly retracted positions in which they are shown in Fig. 3 by reason of the engagement of the latch lever 124 (Fig. 8) with the lever 100. At this time, moreover, the lever 198 (Fig. 3) is held by the latch 204 in its lowered position, and accordingly the clamp fingers 148 are held in their outwardly retracted positions against the lasting straps 48. After mounting the last on the last pin the operator moves the plunger 126 rearwardly and thereby causes the latch lever 124 to release the lever 100, as shown in Fig. 8, whereupon the spring 88 swings the side-lasting mechanisms inwardly to cause the straps 48 to be pressed yieldingly against the upper at the sides of the last by the arms 50 (Fig. 4). The operator then mounts an insole on the bottom of the last. Thereafter he swings the arm 16 forwardly to carry the toe-presser-foot 14 to a position over the toe end of the shoe, and by this movement of the arm the link 30 is moved upwardly to trip the clutch 34 and start the cycle of operations. The upward movement of the link 30 serves, through the connections described, to move the latch 204 into position to release the lever 198, whereupon the spring 202 swings this lever upwardly to carry the roll 222 into engagement with the cam 224. By the upward movement of the lever 198 the arms 182 are swung upwardly, thus causing the springs 174, acting through the rack bars 162 and 142, to move the clamp fingers 148 inwardly and upwardly to positions over the bottom of the shoe, as shown in Fig. 4. Immediately after the starting of the machine the rise 226 on the cam 224 swings the lever 198 downwardly and thereby causes the arms 182 to swing the levers 168 in the directions to move the clamp fingers 148 downwardly and outwardly, thus causing these fingers to clamp the marginal portion of the upper yieldingly against the lasting straps 48 in locations farther outward than the edge of the insole in the manner illustrated in Fig. 5. Near the beginning of the cycle also the heel-presser-foot 12 and the toe-presser-foot 14 impart a short downward movement to the shoe to cause the straps 48 to wipe the upper up the sides of the last, the shoe being shown in Fig. 5 in its depressed position. Thereafter the arms 44 are swung inwardly by the action of the cam 120 (Fig. 8) to cause the lasting fingers 46, acting through the straps 48, to lay the marginal portion of the upper inwardly over the insole into position to adhere to the insole, as illustrated in Fig. 6. In response to the inward swinging movements of the arms 44 the pins 240 on the bars 238 engage the outwardly extending arms 242 of the levers 230 and swing these levers in the directions to cause the pins 234 to impart upward swinging

movements to the inner portions of the holders 140 and the rack bars 142. In this manner the clamp fingers 148 are moved upwardly far enough to insure that regardless of the extent of the upper they will release the upper.

The shoe having thus been lasted at the sides of the shank portion adjacent to its heel end, the side-lasting mechanisms are swung outwardly away from the shoe by the action of the cam 120 and are moved a short distance lengthwise of the shoe toward its toe end into positions to complete the lasting of the sides of the shoe as far as the portion operated upon by the toe-lasting mechanism. Prior to the second operations 15 of the side-lasting mechanisms on the shoe the lever 198 is released by the rise 226 on the cam 224 to cause the clamp fingers 148 to be moved by the springs 174 again inwardly and upwardly to idle positions such as shown in Fig. 4. After the second operations of the side-lasting mechanisms the second rise 246 on the cam 224 imparts downward movement again to the lever 198, thus causing the clamp fingers 148 to be moved downwardly and outwardly to their retracted positions 25 in engagement with the straps 48. These fingers, therefore, and their supports are not in positions to interfere with the action of the shoe-removing mechanism when that mechanism acts on the shoe. Before the rise 246 on the cam has moved far enough to release the lever 198 the arm 16 30 is swung rearwardly from over the shoe and thereby causes the latch 204 to be returned into position to hold the lever 198. Prior to the end of the cycle the rise 246 on the cam passes beyond 35 the roll 222, so that the lever 198 may be swung upwardly in response to forward swinging movement of the arm 16 in the operation of the machine on the next shoe.

Having described the invention, what I claim as new and desire to secure by Letters Patent of the United States is:

1. In a lasting machine, opposite side-lasting mechanisms including flexible lasting straps for engaging the outer face of an upper at the opposite sides of a last and for working the upper into lasted position in the course of a cycle of power operations of the machine, clamp members arranged to engage the inner face of the upper and to clamp the upper against said straps to control it in the lasting operation, and mechanisms spaced from each other beyond the opposite sides of the last and having members arranged to extend inwardly over the straps for moving said clamp members after the starting of the cycle of operations in outward directions widthwise of the last into positions thus to clamp the upper against the straps in locations farther outward widthwise of the last than the edge of an insole on the last.

2. In a lasting machine, opposite side-lasting mechanisms including flexible lasting straps for engaging the outer face of an upper at the opposite sides of a last and for working the upper into lasted position in the course of a cycle of power operations of the machine, clamp members arranged to engage the inner face of the upper and to clamp the upper against said straps to control it in the lasting operation, and means including a power-driven cam for moving said clamp members after the starting of the cycle of operations heightwise of the last and in outward directions widthwise of the last thus to clamp the upper against the straps.

3. In a lasting machine, opposite side-lasting mechanisms including flexible lasting straps for

11

engaging the outer face of an upper at the opposite sides of a last and for working the upper into lasted position in the course of a cycle of power operations of the machine, clamp members arranged to engage the inner face of the upper and to clamp the upper against said straps to control it in the lasting operation, means for moving said clamp members inwardly toward each other widthwise of the last after the work has been presented to the machine but independently of the cycle of operations, and additional means for thereafter moving said members reversely in outward directions into positions to clamp the upper against the straps in locations farther outward widthwise of the last than the edge of an insole on the last as a part of the cycle.

4. In a lasting machine, opposite side-lasting mechanisms including flexible lasting straps for engaging the outer face of an upper at the opposite sides of a last and for working the upper into lasted position in the course of a cycle of power operations of the machine, clamp members arranged to engage the inner face of the upper and to clamp the upper against said straps to control it in the lasting operation, spring means for moving said clamp members inwardly toward each other widthwise of the last after the work has been presented to the machine, and power-operated means for thereafter moving said members reversely in outward directions into positions to clamp the upper against the straps in locations farther outward widthwise of the last than the edge of an insole on the last.

5. In a lasting machine, opposite side-lasting mechanisms including flexible lasting straps for engaging the outer face of an upper at the opposite sides of a last and for working the upper into lasted position in the course of a cycle of power operations of the machine, clamp members arranged to engage the inner face of the upper and to clamp the upper against said straps to control it in the lasting operation, retaining means for holding said clamp members in outwardly retracted positions when the work is presented to the machine and for thereafter releasing said members, spring means for moving the members inwardly toward each other widthwise of the last when they are thus released, and power-operated means for moving said members thereafter reversely in outward directions into positions to clamp the upper against the straps in locations farther outward widthwise of the last than the edge of an insole on the last.

6. In a lasting machine, opposite side-lasting mechanisms including flexible lasting straps for engaging the outer face of an upper at the opposite sides of a last and for working the upper into lasted position in the course of a cycle of power operations of the machine, means for starting the cycle of operations, clamp members arranged to engage the inner face of the upper and to clamp the upper against said straps to control it in the lasting operation, retaining means for holding said clamp members in outwardly retracted positions when the work is presented to the machine, mechanism for causing said retaining means to release the members as an incident to the starting of the cycle of operations, spring means for moving said members inwardly toward each other widthwise of the last when they are thus released, and power-operated means for moving said members reversely in outward directions to clamp the upper against the straps after the starting of the cycle.

12

7. In a lasting machine, opposite side-lasting mechanisms including flexible lasting straps for engaging the outer face of an upper at the opposite sides of a last and for working the upper into lasted position in the course of a cycle of power operations of the machine, a starting member movable by the operator to start the cycle of operations, clamp members arranged to engage the inner face of the upper and to clamp the upper against said straps to control it in the lasting operation, a latch for holding said clamp members in outwardly retracted positions when the work is presented to the machine, means for operating said latch by the movement of said starting member to release said clamp members, spring means for moving the clamp members inwardly toward each other widthwise of the last when they are thus released, and power-operated means for moving said members reversely in outward directions to clamp the upper against the straps after the starting of the cycle.

8. In a lasting machine, opposite side-lasting mechanisms including flexible lasting straps for engaging the outer face of an upper at the opposite sides of a last positioned bottom upward and for working the upper into lasted position in the course of a cycle of power operations of the machine, clamp members arranged to engage the inner face of the upper and to clamp the upper against said straps to control it in the lasting operation, means for moving said clamp members inwardly toward each other widthwise of the last and also upwardly to positions over the bottom of the last after the work has been presented to the machine but independently of the cycle of operations, and additional means for thereafter moving said members reversely in downward and outward directions to clamp the upper against the straps as a part of the cycle.

9. In a lasting machine, opposite side-lasting mechanisms including flexible lasting straps for engaging the outer face of an upper at the opposite sides of a last positioned bottom upward and for working the upper into lasted position in the course of a cycle of power operations of the machine, clamp members arranged to engage the inner face of the upper and to clamp the upper against said straps to control it in the lasting operation, spring means for moving said clamp members inwardly toward each other widthwise of the last and also upwardly to positions over the bottom of the last after the work has been presented to the machine, and power-operated means for thereafter moving said members reversely in downward and outward directions to clamp the upper against the straps.

10. In a lasting machine, flexible lasting straps arranged to engage an upper at the opposite sides of a last, lasting fingers arranged to act through said straps to lay the marginal portion of the upper inwardly over an insole on the last, supports for said fingers movable widthwise of the last to cause the fingers thus to act on the upper, rack bars carried by said supports and arranged to extend widthwise of the last, clamp members carried by said rack bars for clamping the upper against said straps to control it in the lasting operation, other rack bars carried by said supports and mounted for movements heightwise of the last, and connections for moving said first-named rack bars widthwise of the last relatively to said supports by the movements of said other rack bars.

11. In a lasting machine, flexible lasting straps

arranged to engage an upper at the opposite sides of a last, lasting fingers arranged to act through said straps to lay the marginal portion of the upper inwardly over an insole on the last in the course of a cycle of power operations of the machine, supports for said fingers movable widthwise of the last to cause the fingers thus to act on the upper, rack bars carried by said supports and arranged to extend widthwise of the last, clamp members carried by said rack bars for clamping the upper against said straps to control it in the lasting operation, other rack bars carried by said supports and mounted for movements heightwise of the last, operating connections between said other rack bars and the first-named rack bars, and mechanism arranged to act through said rack bars after the starting of the cycle of operations to move said clamp members in outward directions widthwise of the last to clamp the upper against said straps.

12. In a lasting machine, flexible lasting straps arranged to engage an upper at the opposite sides of a last, lasting fingers arranged to act through said straps to lay the marginal portion of the upper inwardly over an insole on the last in the course of a cycle of power operations of the machine, supports for said fingers movable widthwise of the last to cause the fingers thus to act on the upper, rack bars carried by said supports and arranged to extend widthwise of the last, clamp members carried by said rack bars for clamping the upper against said straps to control it in the lasting operation, other rack bars carried by said supports and mounted for movements heightwise of the last, operating connections between said other rack bars and the first-named rack bars, spring means arranged to act through said rack bars to move said clamp members inwardly toward each other widthwise of the last after the work has been presented to the machine, and power-operated means arranged to act thereafter through said rack bars to move said clamp members reversely in outward directions to clamp the upper against the straps.

13. In a lasting machine, flexible lasting straps arranged to engage an upper at the opposite sides of a last, lasting fingers arranged to act through said straps to lay the marginal portion of the upper inwardly over an insole on the last in the course of a cycle of power operations of the machine, supports for said fingers movable widthwise of the last to cause the fingers thus to act on the upper, rack bars carried by said supports and arranged to extend widthwise of the last, clamp members carried by said rack bars for clamping the upper against said straps to control it in the lasting operation, other rack bars carried by said supports and mounted for movements heightwise of the last, operating connections between said other rack bars and the first-named rack bars, retaining means arranged to act through said rack bars to hold said clamp members in outwardly retracted positions when the work is presented to the machine and thereafter to release said members, spring means for moving the members inwardly toward each other widthwise of the last when they are thus released, and power-operated means arranged to act through said rack bars after the starting of the cycle of operations to move said members reversely in outward directions to clamp the upper against the straps.

14. In a lasting machine, flexible lasting straps

arranged to engage an upper at the opposite sides of a last, lasting fingers arranged to act through said straps to lay the marginal portion of the upper inwardly over an insole on the last, supports for said fingers movable inwardly widthwise of the last to cause the fingers thus to act on the upper, clamp members carried by said supports for clamping the marginal portion of the upper against the straps to control it in the lasting operation, and means responsive to the inward movements of said supports for moving said clamp members heightwise of the last relatively to the straps to insure their disengagement from the upper.

15. In a lasting machine, flexible lasting straps arranged to engage an upper at the opposite sides of a last, lasting fingers arranged to act through said straps to lay the marginal portion of the upper inwardly over an insole on the last, supports for said fingers movable inwardly widthwise of the last to cause the fingers thus to act on the upper, clamp members carried by said supports for clamping the marginal portion of the upper against the straps to control it in the lasting operation, devices also carried by said supports for moving said clamp members heightwise of the last relatively to the straps to insure their disengagement from the upper, and means relatively to which said devices are movable by the supports for thus operating them in response to the inward movements of the supports.

16. In a lasting machine, flexible lasting straps arranged to engage an upper at the opposite sides of a last, lasting fingers arranged to act through said straps to lay the marginal portion of the upper inwardly over an insole on the last, supports for said fingers movable inwardly widthwise of the last to cause the fingers thus to act on the upper, clamp members carried by said supports for clamping the marginal portion of the upper against the straps to control it in the lasting operation, levers also carried by said supports and arranged to move said clamp members heightwise of the last relatively to the straps to insure their disengagement from the upper, and members for thus operating said levers in response to the inward movements of the supports.

17. In a lasting machine, flexible lasting straps arranged to engage an upper at the opposite sides of a last, lasting fingers arranged to act through said straps to lay the marginal portion of the upper inwardly over an insole on the last, arms supporting said fingers and mounted for inward swinging movements widthwise of the last to cause the fingers thus to act on the upper, clamp members carried by said arms for clamping the marginal portion of the upper against the straps to control it in the lasting operation, supports for said clamp members mounted to swing relatively to said arms to carry the clamp members heightwise of the last and thus to insure their disengagement from the upper, levers carried by said arms for thus swinging said supports, and members relatively to which the arms are movable for thus operating said levers in response to the inward movements of the arms.

THEODORE P. COURCHENE.
